WATER-CLOSET.

Application filed December 5, 1927, Serial No. 237,684, and in Sweden May 17, 1927.

This invention relates to a water closet in which a thorough flushing takes place automatically, both when the movable part of the seat, after having been pressed down 5 while a person sits on it, automatically resumes its initial position when the person's weight is removed, and also when the movable part of the seat is lowered to its initial position, after having been fully lifted up. 10 As an example, a water closet according to this invention is shown in the accompanying drawings. Fig. 1 shows a vertical section of the closet with all the parts in initial position. Fig. 2 shows the upper part of 15 the closet in vertical section with the seat pressed down and the flushing member in raised position and with the float in lowered position, the tap being open. Fig. 3 shows the upper part of the closet in vertical 20 section with the seat fully lifted up, the flushing member in raised position and with the float also in raised position, the tap being closed. 25 A description of the water closet shown as an example: In or at the upper part of the water closet 1 there is a chamber 2, flushing water chamber, arranged beneath the upper edge 4 of the bowl 3. This chamber is mostly occupied 30 by a member 5, the flushing member, which normally rests on the bottom 6 of the flushing chamber, which bottom in a suitable incline rises to the upper edge 4 of the bowl 3. The bottom surface 7 of the flushing member is 35 made to correspond with the bottom surface of the flushing water chamber. The flushing member 5 is made in the form of a container with greater depth than the flushing water chamber. In the wall of the flushing member 40 which is turned towards the bowl of the closet, is arranged a swingable valve 8 with its valve seat 9. One end of a chain 10 is fastened in the valve, while its other end is fastened in a cover 11, which closes a cap 45 12, which is placed above the flushing water chamber on the closet. The length of the chain 10 is so adjusted, that when the flushing member rests on the bottom of the flushing water chamber, the valve 8 is lifted by 50 the chain 10 from the seat 9. On each side of the flushing member 5 is arranged a two armed lever 13, which is turnable round a pin 14, which is fastened to the closet. One arm of the lever is turnably connected with the flushing member 5

by a pin 15. The other arm of the lever is actuated by a pin press 16, which passes through a hole 17 in the upper part of the closet 1. The seat is in a usual manner made in two parts, the stationary part 18, which is screwed to the closet 1, and the movable part 19. Both parts of the seat are connected with each other by means of hinges 20. By means of the levers 13 and the press pins 16 the movable part of the seat 19 is held a little 60 raised above the closet 1, when the flushing member rests on the bottom of the flushing chamber, Fig. 1. Both arms of the levers and the length of the press pins 16 are adjusted with such a way that when the movable part of the seat 19 is pressed down against the closet, as shown in Fig. 2, the flushing member, owing to the actuation of the press pins 16 on the levers 13, is raised to the desired height 65 by the levers. 70 To the arm of the lever 13, which is joined with the flushing member 5 is fastened one end of a chain 21, which by its other end is connected to the movable part 19 of the seat, and the length of which is adjusted so 75 that when the movable part 19 of the seat is fully lifted up, as shown in Fig. 3, the flushing member 5, by the actuation of the chains 21 on the levers 13, is raised to the desired height. Each fastening point of the chain 80 21 to the lever 13 and the movable part 19 of the seat respectively are so chosen, that when the seat is fully lifted up, these fastening points and the hinge 20, of the movable seat, lie in a straight line, Fig. 3, in 85 such a way that no turning moment takes place on the movable part of the seat. 90 In the flushing chamber there is a float 22, which is fastened to a bar 23, which is connected with one arm of a lever 25 pivotal 95 on a stationary pin 24, the other arm of said lever being connected with a bar 26, which, when being raised, actuates a tap (not shown in the drawing) in such a way that this is opened, and the flushing water is conveyed 100 to the flushing member and the flushing water chamber through the pipe 27. 105 The described closet works in the following manner: When the closet is not being used, the different parts assume the initial position, shown in Fig. 1. The flushing member 5 rests on the bottom 6 of the flushing chamber, and the chain 10 between the valve 8 and the cover 11 keeps the valve 8 open. The 110

- movable seat part 19 is held a little raised from the closet 1, Fig. 1, by the levers 13 and the press pins 16. The chains 21 between the levers 13 and the movable seat part 19 are slackened. The water level in the flushing chamber 2 is at the line $a-a$, whereby the float 22 floats at such a level, that the bar 26 does not actuate the tap, which is consequently closed.
- When one sits on the movable part 19 of the seat, the press pins 16 are pressed against the levers 13 in such a way that these are turned around the stationary pins 14. The flushing member 5 is then raised, and when the seat is entirely pressed down, the flushing member has reached the level, which is shown in Fig. 2. The chain 10 between the valve 8 and the cover 11 is then slackened, so that the valve 8 has fallen down against the seat 9 and tightened against the same. The chains 21 between the levers 13 and the movable part 19 of the seat are also slackened and have thus not actuated the levers 13. The water in the flushing water chamber 2, owing to the raising of the flushing member 5, has sunk from the level $a-a$ shown in Fig. 1 to the level $b-b$ shown in Fig. 2. The weight of the float 22 then acts upon the lever 25, so that this is turned around the pin 24 and raises the bar 26, which then actuates the tap, not shown, so that this is opened and the flushing water streams in through the pipe 27. This flushing water streams into the flushing member 5 and fills this, whereafter it runs over the flushing member's edges to the flushing chamber 2. When the water surface in the flushing chamber 2 has risen to the level $a-a$ (see Fig. 3), the float 22 again floats and actuates the lever 25 in such a way, that the lever is turned around the pin 24, whereby the bar 26 is lowered, the tap not shown is closed and the admission of flushing water ceases. As shown in Fig. 3 both the flushing member and the flushing water chamber are filled with flushing water.
- When one rises from the movable part 19 of the seat, the flushing member, owing to its own weight and the weight of the water it contains, sinks to its initial position according to Fig. 1, whereby the movable part 19 of the seat is raised to its initial position by the levers 13 and the press pins 16. When the flushing member sinks it forces from the flushing water chamber a quantity of flushing water, corresponding to the volume of that part of the flushing member 5 which has been lowered into the flushing water chamber. When the flushing member sinks, the chain 10 is stretched and opens the valve 8 from its seat 9, whereby the amount of water over the water level $a-a$ in the flushing member flows out of the same. The amount of flushing water forced out of the flushing chamber 2, as well as the amount of flushing water flowing out of the flushing member 5 streams to the

closet bowl 3, over the upper edge of the same and along the insides of the bowl to the outlet and causes a thorough and effective flushing.

When the movable part 19 of the seat is lifted, as shown in Fig. 3, the chains 21 are stretched and act upon the levers 13 in such a way that the flushing member 5 is raised, whereby all parts act in the same way, as when the flushing member was lifted, when the movable part of the seat was pressed down, and as described above. As when the seat is entirely lifted, the fastening points of the chains 21 and the turning point i. e. the hinge 20 of the movable part of the seat, come in a straight line, no turning moment on the movable part of the seat takes place, and thus this movable part remains in its lifted position in the same way as an ordinary seat. When the seat is lowered, the flushing member sinks, whereby all the parts act in the same way as when the flushing member sinks, when the pressure on the seat is released, and as described above.

In a closet according to this invention an equally thorough flushing takes place automatically, both when the movable part of the seat after having been pressed down while one is sitting on it, automatically returns to its initial position, when one rises from it, and when the movable part of the seat after it has been fully lifted up is again lowered to its initial position.

Closets, arranged according to this invention, can be made in many other ways than that described as an example, without deviating from the idea of the invention.

Having now described our invention, what we claim as new and desire to secure by Letters Patent is:

1. A water closet of the character described, comprising a flush bowl and a reservoir chamber separated from each other by an overflow wall, a tank suspended within the reservoir and arranged to be lowered into the water chamber to displace the water therein over the said overflow wall, and into the flush bowl, means to elevate the tank above the normal water level in the reservoir maintained by the overflow wall, a valve disposed in the tank and automatically opened and closed by the lowering and raising, respectively, of the tank within the reservoir to discharge the contents of the tank into the reservoir and thence to the bowl, and a float controlled means operating automatically with a drop in the water level in the reservoir to supply water to the tank and reservoir when the said tank is in raised position.

2. A water closet of the character described, comprising a flush bowl and a reservoir chamber separated from each other by an overflow wall, a seat to be raised and lowered over said flush bowl, a tank suspended within the reservoir and arranged to be lowered therein to

displace the water over the overflow wall and into the flush bowl, means operated by the lowering of the seat to rest on the bowl to elevate the tank above the normal water level in the 5 reservoir maintained by the said overflow wall, a valve in the tank and in closed position when the tank is in elevated position, means for automatically opening said valve when the tank is lowered to discharge the water in 10 the tank simultaneously with the displacement of the water in the reservoir by the tank, and a float operating in the reservoir to automatically release a supply of water to fill the 15 tank and reservoir when the water level in the latter is below the normal maintained by said overflow wall.

3. A water closet of the character described, comprising a flush bowl and a reservoir chamber separated from each other by an overflow 20 wall, the bottom wall of said reservoir chamber being disposed at an upward inclination towards the overflow wall, and a tank suspended for upright adjustment in said reservoir and adapted to displace water in the latter into the bowl over the overflow wall when 25 the tank is lowered, said tank having its bottom wall disposed at an inclination corresponding to that of the bottom wall of the reservoir to facilitate the flow of water from

the reservoir to the bowl when being displaced 30 by the tank.

4. A water closet, as claimed in claim 2, in which the means for elevating the tank comprises a lever arm pivoted adjacent the end depressed by the lowering of the seat, an upright member at the latter end of the arm and projecting into the path of the seat in its lower position on the bowl, and a pivoted connection between the opposite end of the arm and said tank. 40

5. A water closet, as claimed in claim 2, in which the means for elevating the tank comprises a lever arm pivoted adjacent one end to the interior wall of the bowl, a button operating in the wall of the bowl and in the path of the said seat in its position on the bowl and connected to the shorter end of the lever arm, the opposite end of the arm being pivotally connected to the side of the tank, and a connection between the longer end of lever arm 50 and the seat to hold the longer end elevated when the seat is in full open position, whereby the tank will be supported in its uppermost position independently of the said button. 55

In witness whereof, we have hereunto signed our names.
